BOWLING PIN SETTING MACHINE

Gottfried J. Schmidt, Pearl River, N. Y., assignor
to American Machine and Foundry Company, a
corporation of New Jersey

Application December 22, 1945, Serial No. 636,737

10 Claims. (Cl. 273—43)

1

This invention relates to bowling pin setting machines and more particularly to completely automatic bowling pin setting machines in which all operations of spotting and respotting pins during the course of play are automatically carried out and balls are returned to the player so that at the conclusion of the spotting or respotting operation, as the case may be, play can be continued from frame to frame under all conditions for the entire game.

This invention relates generally to a machine of the type shown in Schmidt patent, No. 2,346,189, issued April 11, 1944, although its use is not limited entirely to that type of machine any may find application in other bowling pin setting machines.

One of the problems present in a bowling pin setting machine is that of handling the pins and balls with as great rapidity as possible in order that pins can be removed quickly from the pit of a bowling alley and delivered to a station where they are available for transfer to the spotting mechanism. It is also highly desirable that the operation of the pin removing and conveying mechanism be such that the pins be delivered to the storage station or magazine with a minimum of delay in the operation of the machine after the throwing of each ball so that a maximum number of games can be played with a given machine in a minimum of time.

The present invention relates to the solution of this problem and embodies the provision of mechanism which solves this problem and increases the general operating efficiency of the machine. In this manner more games can be played in a minimum of time and there is a net gain to the owner or operator of bowling pin establishments where every minute saved in the operation of a machine is of considerable importance financially.

The present invention, therefore, takes into consideration the desirability of increasing the speed and efficiency of the operation of bowling pin setting machines by simplifying the design thereof through simplification of parts, which results in a decrease in cost, and also a reduction in weight of the machine.

According to my invention I have provided mechanism which makes possible a faster loading of the pin storage or magazine to which pins are delivered cyclically after the throwing of each ball of the frame. Faster loading is the result of improved handling of pins after they are removed from the pit of a bowling alley and delivering them as quickly as possible to the pin

2

storage. That is, during the first ball cycle after the pins have been removed from the pit of an alley, all pins knocked down are immediately transferred to storage or conveyed part way thereto so that some pins are delivered to storage and others are located at intermediate points along the way when the first cycle of operations ceases. After the second ball of a frame is thrown, all pins which were knocked down by the first and second balls are returned to storage and a new set of pins is placed on the alley awaiting throwing of the next ball. It will be seen, therefore, that there is a gain in time resulting from handling pins in this manner due to the fact that it is not necessary to wait until the last ball of a frame is thrown before pins are made available for transfer from the storage to the pin spotters.

In order to make possible the moving of the pins as quickly as possible into the storage magazine, as set forth above, I have provided mechanism which effects the removal of a full set of pins from storage and the delivery of these pins into the pin spotters after the throwing of the first ball of a frame. The removal of each set of pins from storage sets into operation the pin conveying mechanism so that pins knocked down by the first and second balls or the number of balls allotted per frame can be delivered into storage, as described hereinabove, without waiting until the last ball of a frame is rolled.

It is an object of my invention, therefore, to provide an improved automatic bowling pin setting machine of simplified design in which pins are transferred into a storage magazine after each ball of a frame is thrown in order to gain time and make possible a more efficient use and operation of the bowling pin setting machine comprising my invention.

It is a further object of my invention to provide mechanism which results in a faster loading of the storage magazine of a bowling pin setting machine especially in the second ball cycle in order to increase the general efficiency and speed of operation of the bowling pin setting machine comprising my invention.

It is a further object of my invention to provide an improved bowling pin setting machine in which the pin transfer mechanism which transfers pins from the storage magazine to the pin spotting mechanism operates shortly after the first ball of a frame is rolled in order that pins can be conveyed towards or into the storage magazine thereof.

It is a further object of my invention to pro-

vide a bowling pin setting machine having a single cam shaft on which is mounted a plurality of cams, and clutch operating means preferably electro-magnetically controlled, which are responsible for the activation of the clutches at the proper time to effect the desired sequence of operations in the pin handling, distribution, and spotting and respotting during the course of play as the game progresses from frame to frame.

My invention also contributes to a saving of time in the operation of the machine by the provision of means for insuring that the pin spotters of the spotter-respotter table will contain a full set of pins available at all times for setting upon the alley whenever in the course of play it is desired to place a new set of pins on an alley.

The invention also consists in improvements in pin locating or repositioning mechanism for relocating pins at the pin loading station for proper delivery to the several pin transfers which convey pins from the loading station to the pin spotters. In this manner differences in girth or diameter of pins are automatically compensated for and each pin is located substantially directly in the path of movement of a pin transfer. The spreaders which form a part of the repositioning mechanism are operated only after the first ball of a frame is thrown so that the movement of pins into the loading station after the remaining allotted number of balls per frame is not obstructed.

With these and other objects not specifically mentioned in view, the invention consists in certain combinations and constructions which will be hereinafter fully described, and then set forth in the claims hereunto appended.

In the accompanying drawings which illustrate a preferred embodiment of the invention and form a part of this specification, and in which like characters of reference indicate the same or like parts:

Figure 1 is a side elevation of a bowling pin setting machine embodying the invention;

Figure 2 is a front elevation of the same;

Figure 3 is a partial plan view of the machine;

Figure 4 is a partial side elevation, partly in section with parts broken away, showing the mechanism employed for transferring pins from the storage magazine to the setter cups, the pin relocating mechanism, and the mechanism for turning the table to effect a delivery of pins in the setter cups to the alley when the setter table is moved to pin spotting position relative to the alley;

Figure 5 is a plan view of Figure 4 with certain parts omitted for clearness;

Figure 6 is a view of a detail of the sweep safety mount; and

Figure 7 is a wiring diagram showing a suitable circuit for controlling the operation of the several parts of the machine.

In the embodiment selected for purposes of illustration, the machine is driven by a motor 1 (Figure 2) provided with a pulley 10 on which runs a belt 12 continuously driving a pulley 14 mounted on a shaft 16. A worm 18 secured to shaft 16 meshes with worm wheel 20 keyed to a shaft 22 to which is attached the solenoid operated main clutch K₁ of the machine. Clutch K₁, which may be of the well-known Bliss type, is connected with the hub of a gear 24 loosely mounted on shaft 22. Gear 24 meshes with gear 26 (Figures 2 and 3) secured to the main cam

shaft 28 of the machine. Cam shaft 28 is supported in suitable bearings mounted on the side frames of the machine.

Constantly rotating shaft 16 carries a sprocket 29 (Figure 2) on which runs a chain 30 driving a sprocket 32 loosely mounted on shaft 34. The hub of sprocket 32 (Figure 1) is provided with a solenoid operated clutch K₂ similar in construction and operation to clutch K₁ which is actuated at the proper time in the operation of the machine, and engages or disengages sprocket 32 from shaft 34, thereby controlling the drive of the pin distributing mechanism of the machine. The control mechanism for clutches K₁ and K₂ is the same as shown and described in copending Broekhuysen application, Serial No. 627,605, filed November 9, 1945, now Patent No. 2,559,274, granted July 3, 1951. Since this specific mechanism forms no part of my invention, further detailed showing and description is omitted in the interest of brevity.

The mechanism for handling and distributing pins is of the same general construction and similar in operation to that shown in Rundell patent, No. 2,388,707, granted November 13, 1945, for Bowling Pin Setter. This mechanism consists of a transverse ascending conveyor E, shown diagrammatically in Figure 1, which carries pins removed by apron A from pit 5 and discharged into chamber 3 at the rear of bumper W upwardly, and delivers them one by one into a rectifying and aligning conveyor, designated generally C, extending from a point adjacent the top or discharge end of conveyor E to a delivery point adjacent the loading station or storage, such as a magazine M.

Conveyor E is actuated intermittently at the proper time in the cycle of operations of the machine by a sprocket 36 mounted on shaft 34 to deliver pins from chamber 3 at the rear of bumper W to conveyor C which in turn delivers them to the loading station or magazine M. The loading station M of the machine includes a pair of elongated, spaced, rotatable spirals 38 which assemble a plurality of pins, usually ten, for subsequent delivery to the several pin spotters 10. Conveyor C consists of a positively driven belt 64 having its active lap spaced from and extending substantially parallel to a stationary guide member 231. Each spiral 38 carries a sprocket 40 driven by a chain 42 from a sprocket 44 fixed to shaft 46.

Shaft 46 carries bevel gear 48 (Figure 1) meshing with bevel gear 50 mounted on loading mechanism control shaft 34. Chain 42 also drives sprocket 52 mounted on one end of a horizontal shaft 54. The other end of shaft 54 has secured thereto a bevel gear 58 (Figure 2) meshing with bevel gear 60 mounted on a vertical shaft 62. Belt 64, which runs on a pulley 62 secured to the lower end of shaft 60 and on pulley 63 on shaft 65 supported by bracket 67, is the driven part of conveyor C. It is evident, therefore, that by means of the several drives described, conveyors C, E and spirals 38 are all operated simultaneously, and that when shaft 34 is idle these conveying mechanisms are also idle.

Adjacent one of the spirals 38 are located eleven loading contacts or switches 66 (Figure 3) which are normally open as the result of the engagement by pins with pivoted switch operating arms 66a when a predetermined number of pins P, eleven in the illustrated showing, fill the magazine M. The several switches are construct-

ed and arranged and operate in a manner similar to those shown in said Rundell patent, No. 2,388,707, granted November 13, 1945, and further description and showing is deemed unnecessary.

Pins P are lifted out of the magazine or loading station M by means of ten individually and differentially movable grippers 68 suspended from a supporting frame designated generally N, which may be similar in construction to that described in the above mentioned patent to Rupert E. Rundell, No. 2,388,707, granted November 13, 1945. Grippers 68, as described more in detail hereinafter, are moved from aligned positions at the proper time to triangular pin delivery position relative to setter cups 110 on table T to effect the delivery of the pins held thereby into cups 110.

The pin setter-resetter table T illustrated may be of the same general construction as that shown in Nejedly patent, No. 2,298,718, granted October 13, 1942. Table T carries on one side ten pin spotting cups 110 and on the opposite side ten individually laterally movable respotting cups 112. This table is provided with sleeve support members 90 which mount it loosely for turning movement on hollow shaft 84. The ends of shaft 84 are secured to shoes 86 slidably supported in vertical guide channels 88 forming a part of the frame work of the machine.

A gear 92 attached to or formed integrally on one of the support members 90 (Figure 2) meshes with a gear segment 94 pivotally mounted on a stud 96 secured to a bearing plate 98 slideable in one of the vertical guide channels 88 (Figures 1 and 4). Gear segment 94 is provided with an actuating arm 100 (Figures 1 and 4) connected by adjustable rod 102 with one arm of lever 104. The other arm of lever 104 carries a cam follower 106 which runs in a cam track 106a in cam 74. The rocking motion imparted by lever 104 to gear segment 94 effects a 180° turning of the pin setter table T, back and forth in the directions indicated by arrow AA (Figure 1).

Cam 74 which is loosely mounted on the main cam shaft 28 is provided with a hub forming a part of a suitable solenoid operated clutch K₄ such as a well known Bliss clutch, which clutch when actuated effects an engagement or disengagement of cam 74 from the main cam shaft 28. Clutch K₄ is actuated selectively in accordance with requirements arising as a result of the number of pins knocked down by each ball of a frame during the operation of the machine to turn table T from pin receiving position relative to transfer grippers 68 in order to locate pins held in spotters 110 butt end downward for delivery to the playing bed of the bowling alley, and also to move the table back through 180° in the illustrated embodiment at the conclusion of the pin spotting operation in order to relocate the spotters in pin receiving position relative to the pin transfers 68. The contour of cam track 106a accomplishes these desired turning movements of the table.

Table T is turned to position a set of pins held in spotters 110 with their butt ends depending downwardly upon the alley every time a set of pins is to be conveyed to and spotted on the alley. This condition arises after the throwing of the first ball of a frame if a strike is made or after the throwing of the second or last ball of a frame depending upon the number of balls allowed per frame. The specific control mechanism for controlling the operation of the machine insofar as the relation to the selective op-

eration of clutch K₄ in accomplishing the setting of pins on the alley is concerned, may be the same as that shown and described in co-pending Broekhuysen application, Serial No. 627,605, filed November 9, 1945, now Patent No. 2,559,274, granted July 3, 1951. Since it forms no specific part of the invention, further description and showing thereof is omitted in the interest of brevity.

10 As described hereinafter, the turning of the table under the influence of cam 74 is closely associated with the up and down movement of pin transfer grippers 68 in delivering pins to the spotters which is also controlled by cam 74.

15 The setter cups 110 and resetting cups 112 are the same in construction and operation as those disclosed in co-pending Broekhuysen application, Serial No. 627,605, filed November 9, 1945, now Patent No. 2,559,274 granted July 3, 1951, for

20 Bowling Pin Setting Machine. The setter cups 110 and resetter cups 112 are preferably fluid operated. In the machine shown, suction is employed to operate the spotters and respotters. Suction is supplied to spotters 110 at the proper

25 time in the operation of the machine by means of ducts 116 connecting the several pin spotting cups 110 to a source of supply conduit 122 through a solenoid operated control valve 328 of conventional design, preferably supported on the table T, as shown in Figure 3).

30 The respotting cups 112 on the opposite side of table T are also supplied with suction through an interconnected series of conduits 120 (Figure 3) from the source of supply conduit 122 through 35 a solenoid operated suction control valve 328 of conventional design also secured to table T. Suction supply conduit 122 (Figure 3) is connected to a suitable source of suction, such as a suction pump of known design (not shown).

40 Locking mechanism is provided for the purpose of maintaining table T in proper spotter loading, and spotting and respotting positions. For this purpose, gear 92 is provided with a disk 93 attached to or formed integrally therewith having

45 two peripheral notches 95 spaced 180° apart with which in spotter loading, spotting and respotting positions engages the nose of a spring biased lock arm 97 pivotally mounted on one of the pin

50 setter table guide shoes 88. Lock arm 97 which is urged by spring 97a towards locking position relative to notches 95 in disk 93 is provided with a control arm 99 mounting on its free end a roller 101. When arm 99 is engaged and depressed by control finger 103, the nose of lock arm 97 is

55 disengaged from a notch 95 of disk 93 and table T is then free to turn. When released from engagement with finger 103, spring biased lock arm 97 rides on the periphery of the control disk 93 until a notch 95 is moved beneath the nose of lock arm 97, at which time spring 97a pulls it

60 into locking engagement therewith. Control finger 103 (as shown in Figures 1, 2 and 4) is mounted on a short shaft 105 supported by a suitable bearing bracket attached to the frame of the machine. Shaft 105 is actuated to lock and unlock the table turning mechanism by lever 107 attached to an adjustable link 109 connected to a lever 111 mounted on a short shaft 113 mounted in a suitable lug extending from one of the side guide channels 88. Shaft 113 is rocked

65 at the proper time by a cam lever 115 attached thereto. Lever 115 carries a cam follower 117 engaging a cam track 116 in cam 74.

70 Cam 74 is provided with cam tracks 106a and 75 116. One of these tracks 106a is designed to

effect the turning operation of the pin setter table T at the proper time in the sequence of operations of the machine. The other cam track 116 mentioned hereinabove controls the locking mechanism of pin setter table T.

The operations of frame N and transfer grippers 68 carried thereby are resolved into two distinct motions; the back and forth movement of the grippers 68 between magazine M and pin delivery position above setter table T, and the up and down movement of the frame N and the grippers 68 for removing pins from the magazine M and for delivering the same into the spotter cups 110 on the table T. At the predetermined time in the cyclic operation of the machine, suction is created in cups 110 to grip pins conveyed thereto by grippers 68. After locating pins in spotters 110, frame N is raised, and the pins being gripped and held by spotters 110 are pulled out of grippers 68 and remain held in cups 110 awaiting delivery to the alley. The operation and control of clutch K4 is such that whenever spotter cups 110 are empty after the first ball of a frame is rolled, regardless of the number of pins knocked down, a new set of pins is removed from magazine M and delivered into cups 110. This means that the speed of operation of the machine is greatly accelerated because pins do not remain in chamber 3 at the rear of bumper W until at the end of a frame a new set of pins is delivered to the setter cups 110. Instead pins are continuously being returned from chamber 3 to spirals 38 and made available for delivery to the spotters with a minimum loss of time.

Due to the fact that usage of pins results in a decrease in their diameter and because there is some variation in diameters of new pins, when the required number of pins is located between spirals 38 in the loading station or magazine M, the pins may not be located properly with respect to the several pin grippers 68. Mechanism is, therefore, provided for repositioning the pins prior to their removal from the loading station by the grippers 68 in order that each pin may be properly gripped and delivered to the spotters.

As shown in Figure 4 there are provided a plurality of pin relocators or spreaders 280. In the illustrated embodiment, nine spreaders 280 are employed and are mounted on shaft 281 to move upwardly between the depending handle ends of pins supported by spirals 38 into engagement with the pins and shift them laterally relative to the spirals into positions directly in the paths of movement of the centers of the transfer grippers 68. Fixed to shaft 281 is a bell crank lever 282 to one arm of which is connected an adjustable rod 283 pivoted at its other end to lever 284 on shaft 285 on which is fixed a lever 286 provided with a cam follower 287 running in a cam track 288 on cam 74. The other arm of lever 282 has pivotally connected thereto a link 289 which in turn is pivotally connected to a lever 290 mounted on a shaft 292 extending transversely across the machine beneath the spirals 38. Lever 290 is provided with a cam surface 291 adapted to engage with a transverse bar 293 fixed to the underside of an H-member 295 adapted to slide vertically under the influence of cam surface 291 and cam 294 secured to shaft 292 adjacent the opposite side of the machine. H-member 295 is provided with spaced transverse guides 296, 297 (as shown in Figure 4) for guiding the heads of pins moving into the loading station between spirals 28. Guide 297 is provided with cut-outs or openings 298 through which spreaders

280 can move into engagement with pins in the loading station for repositioning the same. H-member 295 is supported at its ends for vertical movement in channels in brackets 244 secured to the side frames of the machine.

In operation, whenever a set of pins is to be removed from the loading station and conveyed by transfer grippers 68 to spotters 110, cam 74 is clutched to shaft 28, spreaders 280 move upwardly to relocate the pins and at substantially the same time cam surface 291 and cam 294 raise H-member 295 to lift the pins a short distance above spirals 38 so that as the transfer grippers move into engagement with the butt ends of the repositioned pins in the loading station or magazine M, downward pressure by the transfer grippers 68 and pins against spirals 38, which would tend to bow the latter outwardly is prevented and at the same time the pins are properly located for positive engagement by the transfer grippers 68.

Since cam 74 is clutched to shaft 28 only after the first ball of a frame is rolled, it is evident that the spreaders 280 and pin support or H-member 295 are operated only at this time. In this way the spreaders 280 are prevented from moving upwardly relative to spirals 38 and interfering with the movement of pins into the loading station or magazine M after the throwing of subsequent allotted balls of each frame and hence there will be no obstruction to the movement of pins into the loading station.

The back and forth motion of the pin grippers 68 on transfer frame N is effected by means of cam lever 124 provided with cam follower 126 running in cam track 127 in cam 128 mounted on cam shaft 28. Cam lever 124 is provided with an arm 130 having pivotally connected thereto gear rack 132 meshing with a gear 133 (Figures 4 and 5) loosely mounted on stud 134 supported in a suitable bracket secured to bracket 82 on one of the side frames.

Gear 133 is formed integral with a gear 135 meshing with gear 136 integral with sprocket 140 on which runs a chain 142 from a sprocket 144 on shaft 146. It will be evident that the rotation of cam 128, through its coaction with cam follower 126 on cam lever 124, effects the oscillation of shaft 146 rotatably supported in vertically movable arms 18 to move pin grippers 68 back and forth on frame N. This operation results in the movement of grippers 68 holding pins removed from magazine M from aligned side by side arrangement to triangular arrangement above spotter cups 110 and the return thereof to a point adjacent magazine M where a dwell in track 127 in cam 128 positions them until in the cycle of operation of the machine grippers 68 again move back and forth along support bars 255 on frame N. However, if a new set of pins is to be removed from the magazine and transferred to the setter table T, the up and down movement of grippers 68 is effected as described hereinafter, and such pins are placed in spotters 110.

The up and down motion of frame N and grippers 68 carried thereby is effected by a cam lever 70. Cam follower 72 on an arm of lever 70 runs in a track 71 in cam 74. The other arm of lever 70 is connected by link 76 to an arm of lever 78 which imparts the vertical up and down motion to frame N and pin grippers 68 at the proper time when clutch K4 is engaged. Cam lever 70 is loosely mounted on cam lever supporting shaft 780 supported at each end by suitable bearing

brackets 82 secured to the frame of the machine. As shown in Figures 4 and 5, there are ten transfer grippers 68. The construction of these grippers is the same throughout so that only one need be described in detail. Each gripper 68 consists of a carriage member 61 provided with flanged rollers 263 running on rails 265 supported by transverse end and center frame members 267 of frame N. Attached to each carriage 61 is a cable 69 running on a driven pulley 271 and a suitable driving pulley 73. Preferably pulleys 73 (Figure 5) have a plurality of grooves in order to obtain the desired frictional engagement between cables 69 and the surfaces of pulleys 73. Since some of the carriages 61 travel a greater distance than others, rails 265 are of different lengths, as shown in Figure 5. Driving gears 141, 143, 145 and 147 are of varying diameters in order to effect the required differential movement of the several carriages 61 from the aligned position shown in full lines to the triangular arrangement, shown in broken lines in Figure 5. Each of these gears drives an appropriately sized gear on a stud shaft supporting one of the pulleys 73. Since the construction of all is the same, only one is described in detail. In Figure 4, gear 147 is shown meshing with gear 149 on shaft 149a suitably mounted on frame N.

Frame N which supports carriages 61 and the associated supporting and driving mechanisms described is mounted for oscillatory movement in a generally arcuate path in a manner similar to that shown in Rundell patent, No. 2,388,707, granted November 13, 1945.

It will be evident from the foregoing that the clutching and unclutching of cam 74 to shaft 28 due to the operation of solenoid actuated clutch K₄, controls the up and down movement of frame N, also the turning of table T, and the locking mechanism therefor, and the operation of the pin spreaders or relocators 280 and the pin supporting device 295.

All other mechanisms of the machine, such as the sweep F and associated guard G, the pin lifting pit apron A, ball cradle L, which delivers balls to transverse runways 6, 7, and the several devices for effecting the down and up movement of table T to and from the alley, and the back and forth movement of pin grippers 68 on frame N are actuated by means of suitable cams secured to the main cam shaft 28.

As shown in Figures 4 and 5, one end of frame N is supported by a pair of spaced levers 75 pivotally mounted on studs 77 in brackets 79 fixed to uprights 88. One end of each of the levers 75 is pivotally connected to a stud 81 in a bracket 83 suitably secured to frame N. The other end of each of the levers 75 is pivotally connected to an adjustable connecting rod 85 attached to the end of the lever 78 loose on shaft 139. A counter balancing spring 87 is attached to each of the levers 75 and to the side frame of the machine.

The movements of table T to and from the pin supporting bed of the alley for setting and/or resetting pins are effected by means of a cam 148 which in the illustrated embodiment is formed integrally with cam 128. Cam 148 is tracked by a follower 150 on lever 152 fulcrumed on shaft 80. One arm of lever 152 is pivotally connected to a rod 153 provided with gear rack 154 meshing with gear 156 fixed to a horizontal shaft 158 supported by suitable bearings attached to the main frame of the machine. On each end of shaft 158 is secured a pulley 160 to which is attached one end of a cable 162, the other end of

the cable being secured to a pin setter table guide shoe 86, mentioned heretofore.

A balance spring 164 encircling shaft 158 (Figure 3) is provided to counterbalance the weight of the pin setter table T. One end of spring 164 is anchored to the frame of the machine; the other end is attached to a flange 166 secured to shaft 158. Pin setter table T carries a cam wedge 168 (Figure 2) employed for the purpose of closing the pin setter table control limit switch 298 when the table reaches its lowermost or pin engaging and lifting position.

Main cam shaft 28 mounts a cam 170 provided with cam tracks 171, 173 on its opposite faces. Cam track 171 in one face of cam 170 is tracked by a cam follower 172 on cam lever 174 which operates the ball lift or cradle L. Cam track 173 on the other side is tracked by a cam follower 176 on cam lever 178 which operates the pit or

pin lifting apron A. Apron A and ball lift L are of the same general construction and operation as disclosed in the Schmidt Patent 2,389,643, granted November 27, 1945. The front end of the pit apron A is elevated by means of a pair of cables 180, each of which is secured to a pulley 182 mounted adjacent an end of horizontal shaft 184 which is oscillated by means of a gear 186 (Figure 1) actuated by a reciprocating gear rack 188, the free end of which is pivotally connected to cam lever 178. The rear end of the pit apron A is wound up on a cylindrical roller 190 mounted on a shaft 192. The latter is oscillated by means of a sprocket 194 and a chain 196, driven by a sprocket 198 mounted on the oscillating shaft 184. The ball cradle L is also raised and lowered by a pair of cables 200, each of which is secured to a pulley 202, both of which are mounted on a horizontal shaft 204, oscillated by means of a gear 206 which is actuated by a reciprocating gear rack 208 pivotally connected to the free end of cam lever 174. The design of cam tracks 171, 173 is such that after each ball of a frame is thrown, the ball lift L and apron A are raised to discharge a ball and pins from the pit for return to a player, and magazine M, respectively, after which apron A and cradle L are returned to the pit 5 (as shown in Figure 1).

Secured to main cam shaft 28 is a cam 210 having cam tracks 211, 213 provided on its opposite faces. Cam track 211 on one side is tracked by a cam follower 212 pivotally mounted on cam lever 214 which is responsible for the movement of guard G to and from the alley after each ball is thrown during the operation of the machine.

Cam track 213 on the other side of cam 210 is tracked by a cam follower 216 on cam lever 218 which actuates the sweep mechanism of the machine. The guard as well as the sweep are of the same general construction as disclosed in Rundell patent, No. 2,250,503, issued July 29, 1941.

The guard G consists chiefly of a guard plate 220 (Figure 1) attached at each end to an arm 222, each arm being mounted on a bracket 224. One bracket 224 is pivoted to a stud 226 held by a bearing bracket 228 (Figure 2), while the other is pivoted to a short shaft 230 also held by a bearing bracket 228. The brackets 224 are connected to each other by a tie bar 232 to which are fastened two cables 233 which in turn are

connected to a third cable 234 which runs over an idler or guide pulley 235 and is anchored to the free end of cam lever 214. Guide pulley 235 is loosely mounted on a horizontal shaft 236 supported in suitable bearings secured to the frame of the machine.

Sweep F (Figure 1) is interconnected with guard G and consists of a sweep board 237 which at each end is supported by a bracket 238. Each bracket 238 is pivoted to a stud projecting from an endless chain 239, reciprocated by a sprocket 240 mounted on horizontal shaft 241 supported by a pair of suitable bearing brackets attached to arms 222. Both chains 239 run over idler sprockets 242 each pivotally mounted on a stud carried by one end of one of the links 243. The other end of each link 243 is pivoted to a suitable supporting bracket 244 secured to the frame of the machine. Shaft 241 is oscillated by means of a sprocket 240a which through a chain 245 is driven from a sprocket 246 (Figures 1, 2 and 3) mounted on shaft 230 on which one of the sweep arm brackets 224 is pivoted (Figure 2). To shaft 230 is secured a sprocket 247 which through a chain 248 is driven by a sprocket 249 mounted on the horizontal shaft 236. The latter carries a gear 250, the hub of which is provided with a solenoid operated sweep control clutch K3 by means of which the gear 250 is engaged with or disengaged from the shaft 236, in a manner similar to that shown and described in the above mentioned co-pending Broekhuysen application for incapacitating the sweep if a pin or pins should walk or move out of the range of the re-spotting cups 112 of the pin setter table T and prevent it from moving into pin lifting position relative to the alley after the first ball of a frame is rolled. Gear 250 is oscillated by a gear rack 251, the free end of which is pivoted to the cam lever 218.

If a pin or pins being removed from the alley is not properly positioned relative to the sweep, it may not be pushed into the pit of the alley at the end of the sweep operation. In such case, on the return movement of the sweep it may press on or bear against a curved surface of a pin, or jam against a pin with such pressure that breakage of parts and damage to the machine result. In order to overcome this condition and allow sweep 237 to yield upwardly away from an obstruction to its return movement a suitable sweep safety mount is provided.

As mentioned hereinabove, brackets 238 which support sweep 237 are pivotally mounted on side chains 239. The desired transverse arrangement of the sweep relative to the alley to be swept is maintained by side links 260 attached to each side bracket 238. Since the side supporting links and their associated connections are the same, only one is described herein. As shown in detail in Figure 6, one end of each link 260 is pinned to a chain 239. The other end is provided with an elongated slot 261 which slides over an elongated guide block 266 fixedly secured to bracket 238 by pin 268. The length of slot 261 is sufficient to allow sweep 237 to clear any obstruction in its return path of movement, as by swinging upwardly in the direction of arrow Y. A spring 273 encircling link 260 and having its ends bearing against washers 275, also encircling link 260 and held against pins 269 and 277 on block 266 and link 260, respectively, urges sweep 237 downwardly into normal operative position.

All cam levers 124, 152, 174, 178, 214 and 219 are loosely mounted on the cam lever supporting shaft 30. To the main cam shaft 28 is also secured a sprocket 252 which by means of a chain 253 drives a sprocket 254 secured to the electrical control cam shaft 255 on which all electrical control cams (not shown) are mounted. These cams, as well as their electrical contact

operating fingers (not shown) are enclosed in a housing H (Figures 2 and 3). Sprockets 252 and 254 driving the control cam shaft 255 are in a 1:2 ratio, i. e., for every two revolutions of the main cam shaft 28, the control cam shaft 255 makes only one revolution. This mechanism is shown and described in the co-pending Broekhuysen application, above referred to. Since it is not a part of the present invention, further description and showing thereof is omitted in the interest of brevity.

Figure 7 shows diagrammatically a combined wiring diagram and control for the machine.

A ball dropping into the pit 5 effects a closing of contacts 300a and 301a of wires 300 and 301, respectively, which in turn causes the engagement of the solenoid operated main clutch K1 located in the hub of gear 24 which is loosely mounted on shaft 22 continuously driven by worm wheel 26 engaging with worm 16 mounted on shaft 16. Shaft 16 has fixed thereto pulley 14 driven through a belt 12 by a pulley 10 on the shaft of motor 4. The engagement of the main clutch K1 causes gear 24 to be driven by shaft 22. Gear 24 in turn drives gear 25 mounted on main cam shaft 28 to which are secured all mechanical cams of the machine with the exception of cam 74 which is engaged with and disengaged from cam shaft 28 by means of solenoid operated clutch K4 attached to the hub of said cam 74, as described hereinabove.

Shaft 16 has secured thereto a sprocket 20 which through chain 30 drives sprocket 32 loosely mounted on the loading conveyor mechanism 35 driving shaft 34 which at the proper time during the operation of the machine is engaged with or disengaged from constantly rotating sprocket 32 by means of a solenoid operated loading clutch K2 attached to the hub of said sprocket 32.

As described hereinabove, the machine is also provided with a solenoid operated sweep clutch K3 attached to the hub of gear 250 for the purpose of engaging or disengaging gear 250 from its support shaft 236 in order to impart the desired oscillating motion to the sweep mechanism shown in Figure 1.

The machine is provided with suitable control mechanism for automatically controlling the operation of the machine in order to carry out its prescribed operations as the play of a game progresses. Since the specific control mechanism does not form a part of my invention, further showing and description thereof is omitted in the interest of brevity. Reference is made to co-pending Broekhuysen application, Serial No. 627,605 filed November 9, 1945; now Patent No. 2,559,274, granted July 3, 1951 for a full description and illustration of the control mechanism.

In Figure 7 there is shown shaft 255 which supports a plurality of control cams (not shown) enclosed in housing H. Shaft 255 carries a sprocket 254 which drives the control cams (not shown) in synchronism and proper ratio by means of a chain 253 engaging with a sprocket 252 secured to the main cam shaft 28. The control box 8 contains all other electrical control apparatus and devices (not shown). These may be similar in construction and operation to those disclosed in the above mentioned Broekhuysen application.

A wire conduit 11 connecting the housing H and the control box 8 is provided. All solenoids of the solenoid operated clutches K1, K2, K3 and K4 are connected to a suitable power line 500.

which also supplies the control box 8 with the necessary current. The action of clutches K₁, K₂, K₃ and K₄ is controlled through wires 501, 502, 503 and 504 respectively, all leading into control box 8 and connected with their respective relays and control apparatus (not shown). Low voltage wires 300 and 301 and wires 510 and 511 also connected to the control box lead to the pit switch and the table limit switch 298, respectively.

At the beginning of a game before throwing a ball, the motor switch is on so that shafts 16 and 22 are rotating, due to their connection with motor pulley 10 described heretofore. The desired number of pins, usually ten, are standing in playing arrangement on the alley, and eleven pins are stored in the loading station or magazine M. As the ball B is thrown and drops into pit 5, a closing of contacts 300a and 301a of wires 300 and 301, respectively, is effected after which the energization of a suitable time relay (not shown) located in the control box 8, causes an engagement of the solenoid operated clutch K₁. Through gears 24 and 26 in the manner described, main cam shaft 28 rotates and effects the following operation of the machine: After the pins have come to rest, table T descends and picks up any standing pins, after which the table ascends again. Sweep F then sweeps any fallen pins on the alley or in the gutters into pit 5. Spreaders 280 and support 295 are operated so that pins in magazine M are repositioned and supported as described hereinabove. As the table moves to its uppermost position, the pin grippers 68 which have, in the meantime, lifted ten properly positioned pins out of the magazine M, move into pin playing arrangement above table T, and deposit the pins carried thereby into the spotter cups 110. Since at this time solenoid K₄ is energized, frame N is raised leaving a set of pins in spotter cups 110, and grippers 68 are returned to their original positions adjacent magazine M. As soon as grippers 68 have returned to this position, the solenoid of clutch K₄ is de-energized to effect a disengagement of cam 74 from the main cam shaft 28 thereby incapacitating the mechanism which raises and lowers frame N relative to spotter cups 110. Table T then descends again and respots the pins picked up before on the alley, and ascends again. During this movement table T also carries the ten pins deposited in the spotter cups 110 by the grippers 68. As soon as ten pins are lifted out of the spirals 38 by the grippers 68 and have moved clear thereof, the solenoid of the loading clutch K₂, on sprocket 32 is energized. This effects the drive of shaft 34 which actuates the loading conveyor mechanisms C, E and 38 and feeds pins from chamber 3 back of bumper W towards and into magazine M. As soon as re-spotting cups 112 have respotted the pins on the alley, table T ascends again and since the first cycle is now completed, all solenoid operated clutches are disengaged through the electrical control mechanism. The player then throws the second ball which ball, upon landing in pit 5, closes contacts 300a and 301a, effecting again the engagement of the solenoid operated main clutch K₁ on gear 24 which in turn through gear 26 drives the main cam shaft 28. The operation of the machine is now as follows:

After the ball is thrown and the pins have come to rest, table T descends and the positions of any standing pins are made known to the player by means of a suitable annunciator (not shown).

At this time respotters 112 are inoperative to lift such standing pins and, therefore, do not pick them up. Table T then ascends, and all pins fallen and standing are swept into the pit 5. 5 Table T, carrying ten pins in its spotter cups, then turns 180° since at that moment the solenoid operated clutch K₄ is engaged again, and descends to place the ten pins in playing or on-spot positions on the alley for the next play and 10 the pins are released from spotters 110, after which table T ascends again and turns 180° to resume its original position. In the meantime all pins are elevated by conveyor E and conveyed by conveyor C into the magazine M which 15 now again holds eleven pins ready for the next play. At the time pins are delivered to magazine M spreaders 280 and H-member 295 are inoperative. This makes it possible for any pins conveyed by conveyors C and E to move into magazine M without interference. After the completion of the cycle, the machine stops and is ready for a new play.

The operation of the machine, as described above, takes place during a normal two ball frame. If a strike is made on the first ball and all pins are knocked down thereby, the ball arriving in pit 5 closes contacts 300a and 301a of wires 300 and 301 in the same manner as in the case of the first ball of any frame, thereby 25 causing the operation of solenoid operated clutch K₁ and the main cam shaft 28 rotates. Table T descends, the annunciator (not shown) indicates that a strike has been made and table T ascends to locate pin spotters 110 carried thereby 30 in pin receiving position relative to grippers 68 which have moved with the required number of located pins from magazine M into pin delivering position above the spotters 110. Sweep F then sweeps the fallen pins from the alley or 35 gutters into pit 5. Frame N which supports the grippers 68 is lowered relative to the spotters 110 and a new set of pins is delivered to the spotters. The frame N is then moved upwardly away from the pins which are gripped by the 40 spotters 110. As soon as the grippers 68 have returned to their original position adjacent the magazine M, clutch K₄ is engaged, again table T is turned 180°, and the table descends to place the ten pins carried in the spotters 110 in playing or on spot position, and the pins are released from the spotters 110 upon the alley after 45 which table T ascends again and turns 180° to resume its original position. In the meantime all pins are elevated from chamber 3 back of bumper W by conveyor E and conveyed by conveyor C into the magazine M. There are now ten pins standing on the alley and the machine 50 is ready for the first ball of the next frame.

The solenoid controlled sweep clutch K₃ is 55 only disengaged at the occasion of an off-center pin after the first ball of a frame is rolled, when the operation of the sweep is undesirable.

The invention above described may be varied in construction within the scope of the claims, 60 for the particular device, selected to illustrate the invention, is but one of many possible concrete embodiments of the same. It is not, therefore, to be restricted to the precise details of the structure shown and described.

70 What I claim is:

1. In a bowling pin setting machine, a magazine for holding a plurality of bowling pins, a pin setter, pin spotters mounted on said setter, pin transfers for gripping, removing and transferring pins from said magazine to said spotters,

mechanism for actuating said transfers after each first ball of a frame is thrown and prior to the rolling of the second ball of a normal two ball frame or the first ball of the next frame if a strike occurs to remove a new set of pins from said magazine and deposit said set of pins in said spotters, and selectively operated means adapted to move said setter to pin spotting position adjacent a bowling alley and locate said spotters in pin delivering position relative to said alley.

2. In a bowling pin setting machine having a magazine adapted to hold a plurality of bowling pins in side by side upright aligned arrangement, a pin setter, spotters on said pin setter, individually and differentially movable pin transfers for gripping and moving pins from said magazine into pin delivery arrangement above said spotters, and mechanism operative only after each first ball of a frame is thrown and before the next ball of the same frame is rolled in a normal two ball frame for actuating said transfers to effect relative vertical movement between said transfers and said spotters whereby said pins in said transfers are removed from said magazine and delivered by said transfers into said spotters and released from said transfers.

3. In a bowling pin setting machine having a magazine adapted to hold a plurality of bowling pins in side by side upright aligned arrangement, a pin setter, spotters on said pin setter, individually and differentially movable pin transfers for gripping and moving pins from said magazine into substantially triangular arrangement above said spotters, mechanism for actuating said transfers after each first ball only of a frame is thrown and prior to the rolling of the next ball of said frame, said mechanism including means for moving said transfers horizontally, and means to effect relative vertical movement between said transfers and said spotters whereby said pins in said transfers are delivered into said spotters, and selectively operated mechanism actuated in response to the number of pins knocked down by the first ball of a frame for controlling the movement of said pin setter to place a new set of pins on said alley or reset pins remaining standing on said alley after a first ball of a frame is thrown.

4. In a bowling pin setting machine having a pin loading station and a pin delivery station, pin transfers for removing pins from said loading station and conveying said pins to said delivery station, mechanism for actuating said transfers to effect the movement of pins to said delivery station after each first ball of the frame is rolled and before the next ball is rolled, said mechanism for actuating said transfers including a cam shaft, a cam fixed to said shaft, a cam loosely mounted on said shaft, and means for connecting said last named cam to said shaft only after each first ball of a frame is rolled.

5. In a bowling pin setting machine having a pin setter, said setter being provided with pin spotters and respotters, a sweep, a guard, a device for removing pins and balls from the pit of a bowling alley, and transfers for conveying bowling pins from a loading station and delivering the same into said spotters, transfer actuating means, cams for actuating said sweep, said guard, and said device, respectively, said transfer actuating means including a cam for operating said transfer actuating means for imparting substantially straight line motion to said trans-

fers, a single cam shaft to which said cams are secured, means for driving said shaft cyclically, a cam for imparting substantially vertical movement to said transfers loosely mounted on said cam shaft, and selectively operated clutch mechanism for connecting said last-named cam to said shaft whenever pins are to be conveyed by said transfers into said spotters, said cams for imparting substantially straight line movement to said transfers and said cam loosely mounted on said shaft being constructed and arranged to coact and provide a combined substantially arcuate path of movement to said transfers in removing pins from said magazine and delivering said pins to said spotters when said loosely mounted cam is connected to said shaft.

6. In a bowling pin setting machine for use with a bowling alley, said machine having a pin loading station including means for supporting a plurality of bowling pins, a pin setter, pin spotters mounted on said setter, pin respotters also mounted on said setter for replacing pins in on or off-spot playing positions on said alley, pin transfers for transferring pins from said loading station to said spotters, mechanism for moving said setter to a position adjacent said alley to locate said respotters in position to grip standing pins after the throwing of each first ball of a frame and for raising said setter, and means for actuating said transfers after the raising of said setter to effect the removal of a set of pins from said station, and the delivery thereof by said transfers into said spotters, said setter moving mechanism including means operative after the delivery of a set of pins to said spotters to lower said setter containing a set of pins in said spotters and lifted pins in said respotters to replace said lifted pins held in respotters on said alley, said last-named mechanism also including means for lowering said setter after the rolling of the last ball of a frame, and means for spotting said pins in said spotters on said alley.

7. In a bowling pin setting machine having a pin magazine, a pin setter having a plurality of pin spotters, conveying means for removing pins from the pit of a bowling alley, and returning said pins to said magazine, a pin transfer including travelling pin grippers for conveying pins from said magazine to said spotters, and mechanism for actuating said transfer after the first ball of a frame is rolled regardless of the number of pins knocked down thereby to remove a set of pins from said magazine and convey said set of pins to said spotters, said mechanism including a selectively operated device for imparting vertical movement to said transfer and grippers, said actuating mechanism also including means for imparting back and forth movement to said grippers, and means operative only when pins are to be delivered from said magazine to said spotters for actuating said mechanism and said last-named means to move said transfer grippers in a substantially arcuate path of travel and deliver pins from said magazine into said spotters.

8. In a bowling pin setting machine having a pin loading station, and conveying mechanism for conveying pins from the pit of a bowling alley to said station, a pin setter, pin spotters mounted on said setter, pin respotters also mounted on said respotter, setter operating mechanism, means for operating said mechanism after the first ball of a frame is rolled for moving said setter to a position adjacent said alley to locate said respotters in position to test for any stand-

ing pins, means for operating said respotters to grip and hold any standing pins, means for raising said setter to cause said respotters to lift said standing pins, a pin transfer, means for actuating said transfer after the first ball of a frame is rolled and while said last-named pins are held by said respotters to deliver a set of pins from said station into said spotters, said setter operating mechanism including means to lower said setter prior to the rolling of the next ball of the same frame with a set of pins in said spotters and reset any lifted pins on said alley in on or off-spot positions, means for operating said respotters to release said lifted pins for relocation on said alley in said on or off-spot positions, and means for actuating said setter operating mechanism to move said setter to pin delivery position adjacent said alley for placing a new set of pins on said alley.

9. In a bowling pin setting machine having a pin setter, said setter being provided with pin spotters and respotters, a sweep, a guard, a device for removing pins and balls from the pit of a bowling alley, and transfers for conveying bowling pins from a loading station and delivering the same into said spotters, transfer actuating means, a cam shaft, cams fixed to said shaft for actuating said sweep, said guard, said device and said transfer actuating means for imparting substantially straight line movement to said transfers respectively, a cam loosely supported on said shaft, said cam having a track for turning said setter to locate said spotters in position to receive pins from said transfers and in position to deliver pins held in said spotters to said alley, said cam also having a track to impart substantially vertical movement to said transfers to effect relatively vertical delivery movement between said transfers and said setter in delivering pins to said spotters, and selectively operated clutch mechanism for connecting said cam to said shaft, said cams for imparting substantially straight line movement to said transfers and said cam loosely mounted on said shaft being constructed and arranged to coact and provide a combined substantially arcuate path of movement to said transfers in removing pins

from said magazine and delivering said pins to said spotters when said loosely mounted cam is connected to said shaft.

10. In a bowling pin setting machine having a pin loading station, and conveying mechanism for conveying pins from the pit of a bowling alley to said station, a pin setter, pin spotters mounted on said setter, pin respotters also mounted on said resetter, means operative after the first ball of a frame is rolled for moving said setter to a position adjacent said alley to locate said respotters in position to test for any standing pins, means for operating said respotters to grip and hold said standing pins, mechanism for raising said setter to cause said respotters to lift said standing pins, a pin transfer, means for moving said transfer to convey a set of pins from said station to said spotters while said setter is raised and said pins in said spotters are held thereby, said last-named mechanism being also constructed and arranged to move said table downwardly to reset said pins on said alley and upwardly with pins in said spotters to a position of dwell above said alley, means for actuating said transfer moving means only after the first ball of a frame is rolled to cause said transfer to deliver a full set of pins from said station into said spotters, to make available said pins in said spotters for setting and clear said station for the return of pins knocked down by the first ball of a frame, and means for actuating said setter operating mechanism to move said setter to pin delivery position adjacent said alley to place a set of pins on said alley.

GOTTFRIED J. SCHMIDT.
